UNITED STATES PATENT OFFICE.

LUTHIER L. HIGBY, OF FORT WORTH, TEXAS.

DESIGN FOR A DISPLAY-BANNER.

SPECIFICATION forming part of Design No. 24,521, dated July 30, 1895.

Application filed January 28, 1895. Serial No. 536,495. Term of patent 14 years.

To all whom it may concern:

Be it known that I, LUTHER L. HIGBY, a citizen of the United States, residing at Fort Worth, in the county of Tarrant and State of Texas, have invented and produced a new and original Design for Advertising or Display Banners; and I do hereby declare the following to be a full, clear, and exact description of the same, reference being had to the accompanying drawing, forming a part thereof.

The said drawing is an elevation of an advertising or display banner embodying my new design.

My design relates to the surface ornamentation upon the said banner.

The leading feature of this design consists in the presentation of an absolutely-smooth uniformly-level surface ornamented by series of horizontal and vertical lines thereon, forming rectangular spaces, whereof the largest space is at the center, and with a series of smaller rectangular spaces at each side thereof, and series of other rectangular spaces above and below said central rectangular space.

A represents a rectangular space formed by the vertical lines *a a* and horizontal lines *b b*, said space A occupying the central part of the

banner, and having at each side thereof the spaces B B B, separated and defined by the short horizontal lines *c c c*.

D represents a border-line extending all around the banner adjacent to and parallel with the outer edges thereof, so as to form an inclosure for all of the other lines and spaces of the said design.

Above the central space A and the spaces B B at the sides thereof are other spaces E E E of varying widths, formed by vertical lines *e e* and horizontal lines *f f*, as shown, and below said central and side spaces A B B are other spaces F F F of varying widths likewise formed of vertical lines *g g* and horizontal lines *h h*, as shown, but all within the hereinbefore-named border-line D.

The bottom of the banner is shown ornamented with circular disks or bangles *d d*.

What I claim is—

The design for an advertising or display banner, substantially as shown and described.

In testimony whereof I affix my signature in presence of two witnesses.

LUTHER L. HIGBY.

Witnesses:

J. SHEPHERD,
ROSAMOND LAMON.
